Attorney

UNITED STATES PATENT OFFICE.

JOHN CHABALA, OF CUDDY, PENNSYLVANIA.

CAR-BRAKE.

1,270,377.

Specification of Letters Patent. Patented June 25, 1918.

Application filed February 9, 1918. Serial No. 216,278.

To all whom it may concern:

Be it known that I, JOHN CHABALA, a citizen of the United States, residing at Cuddy, in the county of Allegheny and

5 State of Pennsylvania, have invented certain new and useful Improvements in Car-Brakes, of which the following is a specification, reference being had to the accompanying drawings.

10 This invention relates to certain improvements in car brakes and an object of the invention is to provide a device of this general character especially designed and adapted for use in connection with mine cars, and it 15 is an object of the invention to provide a novel and improved brake which may be readily and conveniently operated by the driver of the car.

The invention also has for an object to 20 provide a novel and improved device of this general character including a block positioned between a pair of wheels together with shoes carried by said block and engageable with the wheels and wherein an 25 operating means is directly engageable with each of the shoes.

Furthermore, it is an object of the invention to provide a novel and improved brake of this general character including a pair 30 of shoes coacting with adjacent wheels together with a retractile member interposed between the shoes for maintaining the same in inoperative position.

The invention consists in the details of 35 construction and in the combination and arrangement of the several parts of my improved car brake whereby certain important advantages are attained and the device rendered simpler, less expensive and 40 otherwise more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view in side elevation illustrating a mining car having a brake applied thereto constructed in accordance with an embodiment of my invention;

50 Fig. 2 is a view in perspective of the hanger and coacting block as herein employed; and

Fig. 3 is a view in perspective of one of

the rock arms and coacting lever or pedal as herein embodied.

As disclosed in the accompanying drawings B denotes the car body provided with 60 a pair of parallel and transversely disposed supporting axles 1, and mounted on the opposite end portions of the axles 1 are the wheels 2 of a conventional type.

Depending from each side of the body B 65 at a point intermediate a pair of wheels 2 is a hanger 3 having a longitudinally disposed slot 4 in its upper end portion through which is directed a member 5 extending outwardly from the side of the body B. By 70 this arrangement it will be perceived that the hanger 3 is capable of endwise movement in a vertical direction in addition to a swinging movement.

Secured to the lower end portion of the 75 hanger 3 is the block 6. Pivotally engaged with the upper portion of the block are the oppositely directed shoes 7 substantially semi-circular in form and which overlie the adjacent pair of wheels 2. Interposed between the shoes 7 and suitably connected therewith, is a retractile member 8 herein disclosed as a conventional coil spring, which serves to normally maintain the shoe 7 out of engagement with the peripheries 85 of the wheels 2.

Pivotally engaged with each of the shoes 7 is a rod 9 having its opposite or outer end portion pivotally engaged with a rock arm 10 rotatably supported by the side of 90 the car adjacent an end thereof.

As herein disclosed, the rock arm 10 is carried by the operating lever or pedal 12. Upon depression of the lever or pedal 12, either by hand or foot, the shoe 7 will be 95 set and at the same time the block 6 will be elevated and caused to frictionally engage both of the wheels 2 to further effect a braking action.

It is preferred that the outer end portion 100 of each of the rods 9 be slightly curved or offset as indicated at 14 so that when the lever or pedal is at the limit of its downward movement, the coacting shoe 7 and block 6 will be locked in set position. 105

From the foregoing description, it is thought to be obvious that a car brake constructed in accordance with my invention is particularly well adapted for use by reason of the convenience and facility with which 110 it may be assembled and operated and it will also be obvious that my invention is

susceptible of some change and modification without departing from the principles and spirit thereof and for this reason I do not wish to be understood as limiting myself 5 to the precise arrangement and formation of the several parts herein shown in carrying out my invention in practice except as hereinafter claimed.

I claim:

- 10 1. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, and means engageable with each of the shoes for causing the same to engage the adjacent wheel and to elevate the block to engage both of the wheels.
- 15 2. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, means engageable with each of the shoes for causing the same to engage the adjacent wheel and to elevate the block to engage both of the wheels, and means coacting with both of the shoes for normally maintaining the same in a released position.
- 20 3. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, means engageable with each of the shoes for causing the same to engage the adjacent wheel and to elevate the block to engage both of the wheels, and means coacting with both of the shoes for normally maintaining the same in a released position.
- 25 4. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, levers supported by the side of the car adjacent opposite ends thereof, and rods pivotally engaged with the shoes and the levers.
- 30 5. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, levers supported by the side of the car adjacent opposite ends thereof, and rods pivotally engaged with the shoes and the levers, the end portions of the rods engaged with the levers being downwardly directed.

vertical movement, a pair of oppositely directed shoes engaged with the block and overlying the wheels, means engageable with each of the shoes for causing the same to engage the adjacent wheel and to elevate the block to engage both of the wheels, and a retractile member interposed between and engaged with the shoes for normally maintaining the same in released position.

4. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, levers supported by the side of the car adjacent opposite ends thereof, and rods pivotally engaged with the shoes and the levers.

5. In combination with a vehicle body, a pair of supporting wheels at a side of the body and in longitudinal alinement, a block positioned between the wheels and supported by the body for swinging movement and vertical movement, a pair of oppositely directed shoes engaged with the block and overlying the wheels, levers supported by the side of the car adjacent opposite ends thereof, and rods pivotally engaged with the shoes and the levers, the end portions of the rods engaged with the levers being downwardly directed.

In testimony whereof I hereunto affix my signature in the presence of two witnesses.

JOHN CHABALA.

Witnesses:

WILLIAM PHILLIPS,
PHILIP GREEN.
